BUBBLE COLUMN

Ralph M. Parsons, Mount Vernon, Ohio, assignor
to The Ralph M. Parsons Company, Mount
Vernon, Ohio, a corporation of Delaware

Application March 2, 1935, Serial No. 8,990

8 Claims. (Cl. 261—114)

This invention relates to bubble columns and more particularly to a new and improved bubble tray for use in oil refining equipment such as fractionating columns, rerun columns or the like.

5 An object of the invention is to provide a bubble tray having the maximum useful area.

Another object is to provide a bubble tray having a simplified means of support.

10 Another object is to provide a bubble tray in which the path of flow is controlled with respect to the position of the bubble caps.

Another object is to provide a bubble tower without external manholes between the bubble trays.

15 Another object is to provide an improved means for removing side cuts.

Another object is to provide a side cut bucket that can be readily attached to any selected 20 bubble tray after the column is assembled.

Another object is to provide a bubble tray that can be assembled from within the tower.

Various other objects and advantages will be apparent as the nature of the invention is more 25 fully disclosed.

Although the novel features which are believed to be characteristic of this invention will be pointed out more particularly in the claims appended hereto, the invention itself will be better understood by referring to the following description, taken in connection with the accompanying drawings, in which certain specific embodiments thereof have been set forth for purposes of illustration. In the description and in the 30 claims certain specific terms have been used for convenience in referring to various features of the invention but it will be understood that they are to be interpreted as broadly as the art will permit.

40 In the drawings:

Fig. 1 is a vertical section through a portion of a bubble column illustrating one embodiment of the invention;

Fig. 2 is a plan view of one of the trays shown 45 in Fig. 1;

Fig. 3 is a section taken on the line 3—3 of Fig. 1;

Fig. 4 is a section taken on the line 4—4 of Fig. 3; and

50 Fig. 5 is a section taken on the line 5—5 of Fig. 3.

The same reference characters denote like parts in the various figures.

The present invention provides a bubble tray for a typical bubble column having a plurality

of vertically spaced trays arranged so that the fluid to be fractionated, either liquid or vapor, is introduced at an intermediate point in the column. The vapor is caused to bubble upwardly through the liquid on the various trays and the liquid fraction passes downwardly to collect at the bottom of the tower from which it may be removed. The vapor may be removed from the top of the tower or as a side cut from any desired tray. In the operation of this type of 5 tower the temperature becomes progressively lower, passing from the bottom to the top of the column. Hence, different fractions condense and separate from the vapors in the various trays. Intermediate fractions having any desired characteristics can be removed as side cuts from selected points in the column.

The features thus far described are typical of a fractionating or rerun column in an oil cracking plant and are accordingly not set forth here- 20 in in detail.

The drawings illustrate a type of tray that is particularly adapted to large columns. In this form each tray 55 is conveniently made in two halves 55a, 55b, which are joined by flanges 66 25 and bolts 67 (Fig. 2). Since the trays are comparatively heavy they may be independently supported in the tower 68 by peripheral flanges 69 attached to said tower as by welding and bolted to 30 said trays by bolts 70.

Each tray is provided with raised flanges 71 forming bubble openings 72, flanges 73 forming downcomer openings 74, and a flange 75 forming a center manhole 76. In this embodiment a pair of diametrically opposite downcomer openings 74 35 are provided and the bubble openings 72 are arranged in two staggered concentric rows. The downcomer openings 74 are pear-shaped so as to occupy the least possible circumferential space. Bubble caps 80, having radial spacing ribs 81, are 40 secured to the flanges 71 as by T-shaped tie rods 82 which span the openings 72 and extend through the caps 80 to which they are secured by nuts 83.

A manhole cover 84 is provided with flanges 85 forming a peripheral recess 86 which seats on the flange 75. A soft packing 87 may be used to provide a tight seal if desired. The cover 84 may be secured by bolts 90 threaded into bosses 88 formed on said cover and engaging lugs 92 which 45 seat over downwardly projecting ears 93 formed on the tray 55.

Downcomers 94 are bolted to the bottom of the tray 55 in register with the downcomer openings 74 as by means of flanges 95 and bolts 96. The 50

downcomers extend to a point below the liquid level on the tray below.

In order to remove a side cut from any desired tray a novel type of bucket is provided which is interchangeable with any downcomer. This bucket is shown as a bucket 100 attached to a downcomer 101 which is shorter than the downcomers 94 by an amount sufficient to provide clearance for the bucket. The bucket 100 is provided with positioning bosses 102 which rest against the bottom of the downcomer 101 to space the bottom of the bucket therefrom, and with a pair of inner walls 103 of less height than the outer walls 104 and defining openings 105 on opposite sides of the downcomer 100 through which the excess liquid overflows to the tray below at a point adjacent the downcomer and onto the area of the tray below which is adapted to receive liquid from the downcomer. The outer walls 104 are provided with a pair of tapped holes 106 to receive a discharge pipe 107 which leads to a tapped hole 108 in the outer wall of the tower 68. The holes 106 are formed in opposite walls of the bucket 100 so as to provide for right or left hand assembly of the discharge pipe 107. The one which is not used for this purpose may be closed by a plug 109. Suitable holes 108 may be formed in the tower 68 at all trays if desired and the unused holes may be closed by a suitable plug. This permits the bucket 100 to be mounted on any desired tray with a minimum amount of labor. The bucket is attached to the downcomer 101 by bolts 110 which extend through the bottom of the bucket into flanges 111 formed on the downcomers.

In assembling this type of column the trays are lowered in halves and are bolted together and to the flanges 69, beginning at the bottom tray. The workman bolts each tray in place and stands thereon while bolting the next tray. The bubble caps 80 and the manhole covers 84 may be stored on the proper trays until the trays are all in place. The workman then assembles the bubble caps 80 beginning at the top tray and when each tray is finished positions the manhole cover and secures the same from below, finally leaving from a suitable opening (not shown) at the bottom of the tower. Certain selected trays are provided with side cut buckets 100. As these trays are reached suitable connections of the pipe 107 are made to the outer wall of the tower.

Thereafter, the column may be entered from the bottom for purposes of maintenance or to change the position of the side cut buckets, the manhole covers being successively removed in ascending the column.

The above described construction permits standardization of all parts regardless of the position of the side cut buckets and eliminates manholes in the tower wall between trays. In order to install a bucket at any tray it is only necessary to remove a downcomer 94 and to substitute a downcomer 100 with the bucket attached thereto. It is obvious that the number and arrangement of bubble openings and of the downcomers may be varied to suit requirements in any particular installation. In the form shown two concentric rows of bubble openings and two diametrically opposite downcomers are associated with each tray. Successive trays are displaced 90° so that liquid received from one downcomer flows over one fourth of the tray to the next set of downcomers.

In operation, the liquid is received on each tray from the downcomers 94 of the tray above and

rises to a level such that the bottom of the downcomer is sealed thereby. As the flanges 71 and 73 are of the same height, the liquid rises above the top of the flanges 71 before it can overflow over the flanges 73 and discharge through the downcomer opening 74 to the tray below. The liquid is prevented, however, by the vapors rising through the openings 72, from overflowing the flanges 71 and passing through said openings 72. As the liquid passes over the tray from one downcomer 94 to the opposite opening 74, it is directed by the flange 75 over the various openings 72 in contact with the vapors which pass upwardly through said openings and bubble up through the liquid around the caps.

As the process proceeds, the vapors accumulate at the top of the column and may be removed while the liquid collects at the bottom of the column. A side cut may be tapped off from any intermediate tray by substituting a downcomer 101 and its bucket 100 for a downcomer 94 and connecting the discharge pipe 107 to the corresponding tapped hole 108 in the outer wall of the tower.

The number and arrangement of the downcomers and bubble caps may be varied as desired, depending on the operating requirements. The tower may be easily assembled and may be readily entered for inspection or repair. The construction is such that the side cut buckets may be located at any desired tray after the tower has been assembled and without making any substantial alterations therein. The various parts may be standardized and at the same time the operation may be altered as desired to meet various plant requirements.

It is to be noted that the positioning of the manhole in the center and the bubble openings at the outside utilizes the available area to the best advantage. Furthermore, the inactive area at the periphery is reduced to a minimum.

It is to be understood that a sufficient opening must be provided at the top of the tower to permit the trays to be lowered therethrough, which may be closed by a suitable cover when the trays have been assembled. The tower may, for example, be provided with a separate head which may be attached to the tower in any suitable manner as by welding. Access to the bottom of the tower may be afforded by a separable bottom which may also be attached in any suitable manner.

Although certain specific embodiments of the invention have been described for purposes of illustration, it is obvious that various modifications may be made therein by a person skilled in the art and that the invention is only to be limited in accordance with the scope of the following claims when interpreted in view of the prior art.

What is claimed is:

1. In combination, a bubble tray, a downcomer carried thereby through which liquid is discharged, a side cut bucket attached to said downcomer and adapted to receive liquid therefrom, said bucket having spacing lugs adapted to rest against the bottom of said downcomer to provide clearance for the discharge of liquid, having bottom openings outside of said downcomer surrounded by walls over which liquid can overflow to another tray, and having means to discharge liquid to a point beyond said tray.

2. In a bubble tower, in combination, a plurality of spaced bubble trays, a downcomer associated with each tray, certain downcomers extending to a point below the liquid level on the tray be-

low, other downcomers having side cut buckets associated therewith and being interchangeable with said first downcomers whereby a side cut can be taken from any selected tray after the 5 tower is assembled.

3. In a bubble tower, in combination, a plurality of spaced bubble trays, a downcomer associated with each tray, certain downcomers extending to a point below the liquid level on the tray 10 below, other downcomers having side cut buckets associated therewith and being interchangeable with said first downcomers whereby a side cut can be taken from any selected tray after the tower is assembled, said buckets being secured to said 15 last downcomers, having bottom openings on opposite sides of the downcomers surrounded by walls over which the liquid overflows to the tray below, and having a discharge pipe leading to the outside of said tower.

20 4. In a bubble tower, in combination, a plurality of spaced bubble trays, a downcomer associated with each tray, certain downcomers extending to a point below the liquid level on the tray below, other downcomers having side cut buckets associated therewith and being interchangeable with 25 said first downcomers whereby a side cut can be taken from any selected tray after the tower is assembled, said buckets having overflow means discharging to the tray below adjacent the downcomer, and having a discharge pipe leading to the 30 outside of the tower.

25 5. In a bubble tower, in combination, a plurality of spaced bubble trays, each tray having a central manhole and bubble openings disposed there-around, a raised circular flange around said man-hole to confine the liquid to the circular path around said bubble openings, a manhole cover seated on said flange and means to secure said cover from below, comprising depending lips 35 formed on said tray, members seated on said lips and bolts carried by said members and threaded into said cover.

40 6. In a bubble tower having a circular outer

wall, in combination, a plurality of spaced bubble trays having bubble openings therein, bubble caps associated with said openings, a downcomer associated with each tray, certain downcomers extending to a point below the liquid level on the 5 tray below, other downcomers terminating above the bubble caps of the tray below, said last downcomers having side cut buckets associated therewith and being interchangeable with said first downcomers whereby a side cut can be taken 10 from any selected tray after the tower is assembled.

7. In a bubble tower having a circular outer wall, in combination, a plurality of spaced bubble trays having bubble openings therein, bubble caps 15 associated with said openings, a downcomer associated with each tray, certain downcomers extending to a point below the liquid level on the tray below, other downcomers terminating above the bubble caps of the tray below, said last downcomers having side cut buckets associated therewith and being interchangeable with said first downcomers whereby a side cut can be taken 20 from any selected tray after the tower is assembled, said side cut buckets having chambers 25 around said downcomers adapted to receive and store a quantity of liquid, having discharge openings on opposite sides of said downcomer, walls around said openings having overflow means associated therewith to discharge liquid to the tray 30 below, and a liquid discharge pipe leading from said bucket to the wall of said tower.

8. In a bubble tower, in combination, an outer circular wall, a plurality of bubble trays in said tower, side cut buckets associated with certain 35 selected trays, said wall having tapped holes between said trays, each hole being adapted to receive a connection with the corresponding side cut bucket whereby the location of the side cuts can be changed without altering the exterior of 40 said tower.

RALPH M. PARSONS.
